UNITED STATES PATENT OFFICE.

SAMUEL HOGG WILSON, OF GLASGOW, SCOTLAND.

TROUGH AND SPLASH GUARD FOR ROTARY POLISHING OR ABRADING DEVICES.

Application filed December 21, 1926, Serial No. 156,184, and in Great Britain September 26, 1925.

This invention relates to troughs used in connection with rotary abrading or polishing devices; and the invention though having reference to such troughs in general relates particularly to the troughs used in connection with machines for grinding, polishing and similarly treating dentures. With such machines, when the denture being treated is held by the operator against the revolving abrading member, the spray or dust flung off thereby is apt to be deposited in an objectionable manner about the person of the operator.

According to the present invention, I provide a trough having a pivotal splash guard capable of adjustment in two directions so as to suit variations in the diameter, shape, or the location within the trough of the abrading or polishing member.

Preferably the splash guard consists of a narrow tapering canopy mounted upon a fixed spindle spanning the sides of the trough, so that whilst the sprayed substance is prevented from being deposited on the person of the operator, the latter nevertheless is permitted free access to the work and a clear view thereof. The guard can be moved by hand towards or away from the abrading or polishing member and when so moved can be automatically retained in its adjusted position.

With the splash guard referred to above, a second splash guard may be combined, this guard consisting of a shield which bridges the sides of the trough and projects from the inner surface thereof at the back.

An embodiment of the invention applicable to machines for grinding, polishing and similarly treating dentures will now be described by way of example and with reference to the annexed drawing, in which:

Fig. 1 is a side view of the said embodiment, part of the trough being broken away for clearness;

Fig. 2 is a front view of the embodiment;

Fig. 3 is an end view of a modification of part of the embodiment shown in Figs. 1 and 2;

Fig. 4 is a half sectional front view corresponding to Fig. 3.

Figs. 5 and 6 are transverse and longitudinal sections respectively of a second modification of the part shown in Figs. 3 and 4.

Referring to the drawings:

A sheet metal trough 1 for a rotary abrading or polishing member A is made of crib

shape (see Fig. 1), being formed with a base or pedestal 2 on which to rest and with a rear portion 3.

When the abrading member A is in use, abrading material such as powdered pumice stone mixed with water is contained in the trough 1 in the usual manner, and the curved shape of the rear portion 3 and bottom 4 of the trough ensures that the material will always gather at the bottom of the trough ready to be lifted and applied by the operator.

On the rear portion 3 of the trough 1, a shield 5 is provided, this shield being composed of a dished piece of strip metal arranged to bridge the sides of the trough and project from the inner surface at the back. Above the said shield, is disposed a fixed spindle 6 of square (or other noncircular) section which spans the sides of the trough and on which is turnably mounted a narrow tapering canopy 7, which, when in use, extends forwardly from the back of the trough over the abrading member.

The canopy 7 is capable of horizontal adjustment on the fixed spindle 6, and in order that the said canopy may also be adjusted about the said spindle 6, and, virtually, radially of the abrading member, mechanism is provided within the drum 8 of the canopy to retain the latter in the different positions to which it may be turned. This mechanism may consist of the means now to be described with reference to Figs. 1 and 2 or 90 may comprise the modifications hereinafter described with reference to Figs. 3 and 4, and Figs. 5 and 6.

In the means shown in Figs. 1 and 2, two discs 9 are mounted so as to be slidable but non-rotatable on the fixed spindle 6, within the drum 8, and the said discs are forced apart by a spring 10 so that their outer surfaces press against the inner surfaces of the ends 11 of the drum. The friction set up 100 between the said surfaces is sufficient to maintain the canopy 7 in any radial position in which it may be placed, whilst permitting such radial adjustment to be made with ease.

The modification of the mechanism shown in Figs. 3 and 4, comprises a hollow spool 12 which is slidable but nonrotatable on the spindle 6 of square section and has a series of holes 13 formed in the collar 14 thereof (Fig. 4). The holes 13 are set uniformly 110 at equal radii around the squared spindle 6 and in the end 11 of the drum 8 a single

hole 15 is formed in such a manner that by the rotation of the drum 8, the said hole 15 is brought successively into register with the holes 13 in the collar 14 of the spool 12. By 5 thus bringing the hole 15 into register with a particular hole 13 in the collar 14, the canopy 7 can be maintained in various radial positions on the spindle 6, by passing a pin 16 through the holes 13 and 15 in register. 10 Preferably the pin 16 is loosely attached to the canopy 7 or trough 1 by a small chain 16^a.

The modification shown in Figs. 5 and 6 comprises a stationary toothed segment 17 carried by the fixed spindle 6, and a rod 18 15 pressed into contact with the teeth of the said segment by springs 19 secured within the drum 8, the rod 18 being carried in radial slots 20 (Fig. 5) formed in the ends 11 of the drum 8, which as aforesaid is rotatable 20 and slidable on the fixed spindle 6. The action of the springs 19 is such that while they constrain the rod 18 to engage firmly between the teeth of the stationary segment 17, they permit the said rod to ride 25 over the said teeth on rotative movement of the canopy in either direction.

It will be obvious that a narrow canopy as hereinbefore described does not prevent light from reaching the work, though it effectively prevents the abrading material 30 from being deposited on the person of the operator no matter what may be the size, shape, or location within the trough of the abrading member. For example, when a 35 new abrading member is fitted, the canopy 7, of course, is raised, but when the said member becomes smaller due to continued use, the canopy can always be set in its correct operative position relative to the said member. If desired a small sponge or brush 40 may be fitted within a pocket 21 on the point of the canopy 7 for the purpose of cleaning the abrading member. In addition, a small rest 2^a may be provided on the trough to 45 support the denture or other article being ground or polished.

I claim:

1. In rotary abrading devices, the combination of a rotatable shaft and any one of 50 a number of interchangeable abrading members adapted to be supported thereby, with a broad trough, a spindle fixed in and spanning the sides of the trough, a narrow can-

opy 55 slidable and turnable by hand on the said spindle, and means whereby the canopy when turned about the spindle is automatically retained in its adjusted position.

2. In rotary abrading devices, the combination of a rotatable shaft and any one of 60 a number of interchangeable abrading members adapted to be supported thereby, with a broad trough, a spindle fixed in and spanning the sides of the trough, a narrow canopy 65 slidable and turnable by hand on the said spindle, a pair of discs slidable and non-rotatably mounted on the said spindle, and spring means whereby the said discs are forced apart from each other so as to press frictionally against a portion of the canopy.

3. In rotary abrading devices, the combination of a rotatable shaft and any one of 70 a number of interchangeable abrading members adapted to be supported thereby, with a broad trough of which the bottom and back are curved, a base for the trough, a 75 spindle fixed in and spanning the sides of the trough, a narrow canopy slidable and turnable by hand on the said spindle and arranged in spaced relationship to the back of the trough, a shield adapted to bridge 80 the sides of the trough and project from the back thereof underneath the said canopy, and means whereby the canopy when turned about the spindle is automatically retained in its adjusted position.

4. In rotary abrading devices, the combination of a rotatable shaft and any one of 85 a number of interchangeable abrading members adapted to be supported thereby, with a broad trough of which the bottom and back are curved, a base for the trough, a 90 spindle fixed in and spanning the sides of the trough, a narrow canopy slidable and turnable by hand on the said spindle and arranged in spaced relationship to the back of the trough, a shield adapted to bridge 95 the sides of the trough and project from the back thereof underneath the said canopy, a pair of discs slidable and non-rotatably mounted on the said spindle, and spring means whereby the said discs are forced apart from each other so as to press frictionally against a portion of the canopy.

In testimony whereof I affix my signature.

SAMUEL HOGG WILSON
